[57] CLAIM

The ornamental design for a wrist watch case, as described and shown.

DESCRIPTION

FIG. 1 is a top right front perspective view of a wrist watch case showing my new design; the broken line showing of the band is for illustrative purposes only and forms no part of the claimed design;

FIG. 2 is a front elevational view;

FIG. 3 is a left side elevational view;

FIG. 4 is a bottom plan view; and

FIG. 5 is a rear elevational view thereof.

FIG. 1

FIG. 2

FIG. 3
